HARRY E. AINE, OF RICHMOND, CALIFORNIA.

MACHINE FOR WINDING PIPES OR PIPE-COVERINGS.

1,137,943.

Specification of Letters Patent.

Patented May 4, 1915.

Application filed June 14, 1913. Serial No. 773,711.

To all whom it may concern:

Be it known that I, HARRY E. AINE, a citizen of the United States, residing at Richmond, in the county of Contra Costa and State of California, have invented certain new and useful Improvements in Machines for Winding Pipes or Pipe-Coverings, of which the following is a specification.

The present invention relates to improvements in pipe winding machinery and more particularly to that type of machine adapted for constructing wooden, wire wound, endless stave pipe in the ditch or place where used, and the invention has for its principal objects to construct a machine which is capable of tightly winding a continuous spiral coil of wire about a pipe as the same is constructed, one which is so constructed as to be mounted on a formed pipe for rewinding the same should the binding wire break; and one which is also capable of being adjusted over an assembled pipe when it is desired to cover the same with an endless wire wound wooden stave covering or protector without interrupting the assembled structure.

The invention consists primarily in constructing all parts which surround the pipe in sections, that the same may be employed for winding a stave pipe as the same is assembled, or may be mounted on a constructed or laid pipe without cutting the same, should it be desired to rewind the same or provide the same with an additional covering or protector.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction, within the scope of the claims, may be resorted to without departing from the spirit or sacrificing any of the advantages of the invention.

To more fully comprehend the invention, reference should be had to the accompanying drawings in which is disclosed one form of my invention employed in winding a protecting covering about an assembled pipe, and in which—

Figure 1 is a partly broken side elevation of my improved winding apparatus. Fig. 2 is a side view of the winding device with the pipe in section and disclosing the steady-

means for the same. Fig. 3 is a sectional view taken on line 3—3—Fig. 2, disclosing the adjustable pitch giving bars. Fig. 4 is a view in detail of the winding wire tension device. Fig. 5 is a cross section of the toothed annulus taken on line 5—5 of Fig. 2, disclosing the supporting rollers operating in the grooves at the sides of the annulus.

Referring more particularly to the several figures of the drawing, wherein like reference numerals indicate corresponding parts throughout the several views—1 indicates a suitable pipe, preferably of metal, about which is positioned the wooden covering composed of the staves 2 which are positioned around the same with the abutting ends of engaging staves arranged in staggered relation to each other, and which are retained in position about the pipe by an endless spiral winding of wire.

For the purpose of winding the assembled covering, I employ the semi-cylindrical shells 3 and 4 adapted to encircle the staves or covering in slight spaced relation thereto, and said shells are provided on their adjacent meeting edges with bolt flanges 5 through which extend the headed bolts 6, carrying at their ends the nuts 7, between which and one of the flanges are interposed the coiled springs 8, which serve to force the semi-cylindrical shells together about the covering. Surrounding the semi-cylindrical shells and secured thereto is a suitable annular gear formed of the two semi-cylindrical sections 9 and 10, the ends of which overlap and are secured together by suitable transversely extending bolts 11, which are seated in the annular channels 12 formed in the opposite side walls of the sections. Suitable rollers 13, carried by inwardly projecting studs 14 formed on the inner faces of cheek plates 15, operate in the grooves or channels 12 and the upper ends of the cheek plates are connected to a laterally projecting arm 16, which is connected at its end through a link 17 with a suitable spring arm or supporting member 18 carried by a truck 18', the structure being hereinafter termed a dolly, and the same is movable on a suitable trackway 19 positioned at one side of the ditch in which the pipe or covering is being constructed, which permits of the advancing of the winding apparatus on the pipe as the wire is wound thereon. Power is transmitted to rotate the annulus by a suitable pinion 20 to which power may be transmitted from

any suitable source, such as a motor 20 or other power generating device.

From the above description it will be apparent that by constructing the shell of two semi-circular halves and clamping the same about the pipe that no supporting structure is needed and that the arm 16 and dolly will maintain the driving mechanism stationary relative to the annulus and the shell, and will 10 at the same time permit the same to move longitudinally of the covering to properly wrap the wire therearound.

Positioned between the inner surfaces of each of the semi-circular shells 3 and 4 and 15 the staves 2, and secured midway of their length to the pivot pins 21 carried by the shells, are a plurality of equidistant pitch giving bars 22, preferably V-shaped in cross section and curved to conform to the inner 20 surface of the semi-cylindrical shells. These pitch giving members project inwardly and substantially act as threads when embracing the exterior surface of the staves. The corresponding ends of the pitch giving bars 25 carried by the respective shells are pivotally secured to plates 23 provided with studs 24 which operate in slots 25 formed in the shells, and the opposite adjacent ends of the bars are also pivotally connected to plates 26 carrying studs 27 which are slidably 30 mounted in grooves 28 formed in the shells, and said studs 27 carry on their outer ends angle plates 29 through which extend the bolts 30, which are adjustably retained in 35 position relative to other angle plates 31 secured to the exterior of the shells by the nuts 32. It will be apparent that by adjusting the nuts 32 the same will operate the plate 26 associated therewith, and the 40 inclination of the pitch giving bars associated with one of the semi-circular shells will be varied simultaneously, and that the adjusting of said pitch giving bars may be accomplished while the structure is in operation and without removing it from the structure which is being wound.

The wire as wound onto the staves passes through a tension device mounted on the exterior surface of one of the shells and the 50 same consists of a pair of longitudinally spaced plates 33, flanged at their lower ends, and secured to the shell by the bolts 34, and rotatably supported between the plates are the spaced, grooved supporting rollers 35 55 preferably three in number, between which are positioned the tension rolls 36 carried by journals 37, which operate in blocks 38, slidably mounted in slots 39 formed in the plates 33. Adjusting screws 40 threaded 60 through flanges 41 at the upper edges of the plates 33 provide the adjusting means for the tension rolls.

The operation of the apparatus is as follows:—The staves are positioned about the pipe it is desired to protect and temporarily

retained in position in any suitable manner, and the semi-circular shells 3 and 4, each carrying the V-shaped pitch giving bars 22, are placed around the staves being retained in position by the bolts 6. The sectional 70 annulus 9 is detachably secured over the shells 2 and 3, the parts of the annulus being secured together by the bolts 11, and the annulus and shells are rotated to advance spirally and progressively along the 75 staves by power transmitted through the pinion 19. Wire 44 from a reel 45 is lead around below the covering between the reel and the ends of the semi-circular shells 3 and 4, and upwardly, as at 46, through the 80 tension device and passing between the rollers 35 and 36, thence through a perforation 46' in the shell 3 and onto the exterior surface of the staves. One end of the wire is secured to the staves in any suitable manner and power is transmitted through the pinion 19 to revolve the annulus. This in turn rotates the semi-cylindrical shells 3 and 4 around and around the casing, and the engagement of the pitch giving bars 22 85 slightly biting into the exterior surface of the covering causes the entire wire winding mechanism to advance regularly and progressively longitudinally of the covering or protector. It is apparent that by the 90 annulus rotating in the direction as in Fig. 1, the wire 44 will be tightly wound around the protector or covering and by reason of the spiral advance of the shells about the covering or protector, the dolly will be 95 automatically advanced along the track and will prevent the movement of the motor 20 and pinion 19 in the direction of rotation of the annulus.

While I have shown a structure wherein 105 the semi-circular shells are detachably secured to the annulus and are tightly encircled by the same, it will be apparent that the same annulus may be employed with other shells of less diameter than those 110 shown by simply positioning spacing blocks between the annulus and the shell.

It will also be apparent that the machine as at present constructed is capable of being positioned over a laid or constructed 115 pipe without cutting the same should it be desired to provide a wooden stave covering for the pipe, or the machine is equally adapted for constructing endless stave, wire wound pipe in the ditch or place where used.

Having thus described my invention what I claim as new and desire to protect by Letters Patent is:—

1. A wire winding apparatus including an annulus formed in sections, a shaft adapted to drive said annulus, means for supporting said shaft including spaced cheek plates, each carrying rollers engaging beneath flanges formed on the annulus, means supported by one of said cheek plates for driv- 125 130

ing said shaft, a beam to which the cheek plates are secured, and a wheeled support connected to the end of said beam remote from the cheek plates.

- 5 2. A wire winding apparatus including an annulus formed in sections, a shaft adapted to drive said annulus, means for supporting said shaft including spaced cheek plates, each carrying rollers engaging beneath flanges formed on the annulus, means supported by one of said cheek plates for driving said shaft, a beam to which the cheek plates are secured, a wheeled support, and an arm carried by the support and having a
- 15 connection with said beam whereby the cheek plates and the structure supported thereby are prevented from rotating with the annulus.

- 20 3. A wire winding apparatus including an annulus formed in sections, the sections of the annulus being secured together, a structure encircling shell formed in sections and arranged within the annulus, and resilient connections between the sections.

- 25 4. A wire winding apparatus comprising a rotatable annulus formed in sections and attached together, a cylindrical structure encircling shell mounted within said annulus to be rotated thereby and formed in semi-circular sections secured together, each of said sections provided on its inner surface with pitch giving bars to cause the shell to advance spirally about the structure to be wound, means projecting exteriorly of each of said sections for adjusting the inclination of the pitch giving bars carried thereby, means for rotating said annulus, and means for supplying wire to the structure to be wound.

- 35 40 5. A wire winding apparatus comprising a rotatable annulus, a cylindrical structure encircling shell detachably mounted within

said annulus to be rotated thereby, pitch giving bars mounted on the inner surface of said shell to cause the same to advance spirally about the structure to be wound, means projecting exteriorly of said shell for regulating the inclination of said pitch giving bars, means for supplying wire to the structure to be wound, means for rotating said annulus, an arm extending from said annulus rotating means, and a traveling support associated with said arm for maintaining the same steady.

6. A wire winding apparatus including an annulus formed in sections, the sections of the annulus being secured together, a structure encircling shell embraced by the annulus, said shell being formed in sections, pitch giving bars mounted interiorly of each of the sections of the shell.

7. A wire winding apparatus including an annulus formed in sections, the sections of the annulus being secured together, a structure encircling shell embraced by the annulus, said shell being formed in sections, and pitch giving bars pivotally mounted interiorly of each of the sections of the shell.

8. A wire winding apparatus including an annulus formed in sections, the sections of the annulus being secured together, a structure encircling shell embraced by the annulus, said shell being formed in sections, pitch giving bars pivotally mounted interiorly of each of the sections of the shell, and means for adjusting the pitch giving bars of each section.

In testimony whereof I have signed my name to this specification in the presence of two subscribing witnesses.
